W. GARITY

AUDION ELECTRODE STRUCTURE

Filed March 17, 1923

*Interrogation
William Garity
by his attys Darby & Darby*

UNITED STATES PATENT OFFICE.

WILLIAM GARITY, OF BROOKLYN, NEW YORK, ASSIGNOR TO DE FOREST RADIO TELEPHONE & TELEGRAPH COMPANY, OF JERSEY CITY, NEW JERSEY, A CORPORATION OF DELAWARE.

AUDION ELECTRODE STRUCTURE.

Application filed March 17, 1923. Serial No. 625,911.

To all whom it may concern:

Be it known that I, WILLIAM GARITY, citizen of the United States, residing at Brooklyn, 514 McDonough St., in the county of 5 Kings and State of New York, have made a certain new and useful Invention in Audion Electrode Structure, of which the following is a specification.

This invention relates to an audion electrode structure.

It has for its object the provision of the usual electrode structure which is simple, economical of manufacture and efficient in operation.

15 A further object of the invention is to provide an audion electrode structure which permits the assembling of the audion electrodes with the fewest operations and which at the same time affords rigidity and 20 strength.

Further objects of the invention will appear more fully hereinafter.

The invention consists substantially in the construction, combination, location and 25 relative arrangement of parts, all as will be more fully hereinafter set forth as shown by the accompanying drawing and finally pointed out in the appended claims.

Referring to the drawing:

30 Figure 1 is a plan view of an enlarged plate electrode as originally stamped.

Fig. 2 shows the plate electrode in side elevation after being formed and mounted on its supports.

35 Fig. 3 is a sectional view taken on the line 3—3 of Fig. 2, looking in the direction of the arrows.

Fig. 4 is a sectional view taken on the line 4—4 of Fig. 3, looking in the direction of the arrow.

Fig. 5 is a view in side elevation of a complete audion structure.

Fig. 6 is a front view thereof.

45 The same part is designated by the same reference character wherever it occurs throughout the several views.

It is among the special purposes of my present invention to provide a plate electrode for thermionic vacuum tubes, such as 50 the audion, wherein the plate electrodes may be made from the stampings, and to provide such stampings as the assembly of the plate electrode relative to the other elec-

trodes of the audion structure and relative to the supports thereof may be most expeditiously and efficiently secured.

In accordance with my invention I provide a structure which permits the employment of a horizontal concentric electrode arrangement, that is, where the filament electrode extends horizontally and is surrounded by a spiral coil grid electrode which in turn is surrounded by a cylindrical plate electrode. The filament electrode is illustrated at 1 and is provided with the usual 60 circuit electrode supports 2. The grid electrode which surrounds the filament electrode, but spaced therefrom, is shown at 3 and the terminals thereof are connected by the conducting electrode supports 4. The 70 plate electrode is in the form of a cylinder 5 and is spaced from the grid electrode but surrounds the same and is supported by the electrode supports 6.

I will now describe the method of constructing the cylindrical plate electrode 5 and the means for attaching the same to the supports 6 thereof. The plate electrode 5 is preferably in the form of a stamping as shown in Fig. 1, and is provided with two 80 lips 10 and 11 extending from opposite ends thereof. The lip 11 is provided with lateral extension 12 and longitudinal extension 13. The plate electrode thus formed is rolled into the form of a cylinder so that the electrode supports 6 fit in indentations 14 formed in the edge portion of the plate stamping adjacent the lip 10. The lip 10 thus comes in place between the two electrode supports 6 and bears against the lip 11. The flanges 12 and 13 thereof are thereupon bent around the electrode supports 6 and the lower abutting edges of the lips 10 and 11, respectively, and preferably welded in this position. The top and bottom edges 95 of the stamping 5 are cut away, as shown at 20, to form, when rolled into its cylinder, a space 21 to permit the wire of the grid electrode 3 to extend therethrough for attachment to a support by the grid electrode 100 supports 4.

It will be apparent from this construction that I have provided an exceedingly simple and efficient structure which affords simplicity of manufacture and assembly and at 105 the same time ensures a rigid electrode struc-

ture and a rugged audion structure. The electrode structure thus formed is enclosed in the usual evacuated vessel 30 which is based, as indicated at 31, in the usual well-known manner.

Many modifications and changes in details will readily occur to those skilled in the art without departing from the spirit and scope of my invention as defined in the claims, but having shown and described a structure embodying the principles thereof, what I claim as new and useful and of my own invention, and desire to secure by Letters Patent is:

1. In an audion structure, a plate electrode comprising a blank having tongues extending from opposite edges thereof, the said blank being formed into a cylinder with the tongues positioned against each other, a support for said cylinder, and means for securing said tongues to said support.

2. In an audion structure, a plate electrode comprising a blank having tongues extending from opposite edges thereof, the said blank being formed into a cylinder with the tongues positioned against each other, a support for said cylinder, and means for securing said tongues to said support and to each other.

3. In an audion structure, a plate electrode comprising a blank having tongues extending from opposite edges thereof, the said blank being formed into a cylinder with the tongues positioned against each other, a support for said cylinder, and means forming part of said blank for securing said tongues to said support.

4. In an audion structure, a plate electrode comprising a blank having tongues extending from opposite edges thereof, the said blank being formed into a cylinder with the tongues positioned against each other, a support for said cylinder, and means forming part of said blank for securing said tongues to said support and to each other.

5. In an audion structure, a plate electrode comprising a blank having tongues extending from opposite edges thereof the said blank being formed into a cylinder with the tongues positioned against each other, a pair of supports for said cylinder, and means for securing said tongues to both of said supports.

6. In an audion structure, a plate electrode comprising a blank having tongues extending from opposite edges thereof the said blank being formed into a cylinder with the tongues positioned against each other, a pair of supports for said cylinder, and means for securing said tongues to both of said supports and to each other.

7. In an audion structure, a plate electrode comprising a blank having tongues extending from opposite edges thereof the said blank being formed into a cylinder with the tongues positioned against each

other, a pair of supports for said cylinder, and means forming part of said blank for securing said tongues to both of said supports.

8. In an audion structure, a plate electrode comprising a blank having tongues extending from opposite edges thereof the said blanks being formed into a cylinder with the tongues positioned against each other, a pair of supports for said cylinder, and means forming part of said blank for securing said tongues to both of said supports and to each other.

9. In an audion structure, a plate electrode comprising a blank having tongues extending from opposite edges thereof, the said blank being formed into a cylinder with the tongues positioned against each other, one of said tongues being provided with a lip extending from one edge thereof, a support for said cylinder, said lip being bent around said support to fasten said tongues together and to said support.

10. In an audion structure, a plate electrode comprising a blank having tongues extending from opposite edges thereof, the said blank being formed into a cylinder with the tongues positioned against each other, one of said tongues being provided with a plurality of lips extending from the edges thereof, a plurality of supports for said cylinder, said lips being bent around said supports to fasten said tongues together and to said supports.

11. In an audion structure, a plate electrode comprising a blank having tongues extending from opposite edges thereof, the said blank being formed into a cylinder with the tongues positioned against each other, one of said tongues being provided with a lip extending from one edge thereof, a support for said cylinder, said lip being bent around said support and welded thereto.

12. In an audion structure, a plate electrode comprising a blank having tongues extending from opposite edges thereof, the said blank being formed into a cylinder with the tongues positioned against each other, one of said tongues being provided with a plurality of lips extending from the edges thereof, a plurality of supports for said cylinder, said lips being bent around said supports and welded thereto.

13. In an audion structure, a plate electrode comprising a blank having tongues extending from opposite edges thereof, the said blank being formed into a cylinder with the tongues positioned against each other, one of said tongues being provided with a lip extending from each edge thereof, a pair of supports for said cylinder, two of said lips being bent around said supports, and the third being bent over the edge of the other tongue.

14. In an audion structure, a plate electrode comprising a blank having tongues extending from opposite edges thereof, the said blank being formed into a cylinder
5 with the tongues positioned against each other, one of said tongues being provided with a lip extending from each edge there- of, a pair of supports for said cylinder, two of said lips being bent around said supports and welded thereto, and the third lip 10 being bent over the edge of the other tongue.

In testimony whereof I have hereunto set my hand March A. D., 1928.

WILLIAM GARITY.
